SEMIAUTOMATIC RIFLE

Raymond Frederick Gerfen, Belleville, Ill.

Application April 21, 1943, Serial No. 483,934

1 Claim. (Cl. 42-3)

The present invention relates to new and useful improvements in semi-automatic rifles, and has for its primary object to provide, in a manner as hereinafter set forth, a fire arm of this character comprising novel means whereby the opening of the bolt relative to the firing of the cartridge in the chamber will be controlled.

Other objects of the invention are to provide a semi-automatic rifle of the aforementioned character which will be comparatively simple in construction, strong, durable, highly efficient and reliable in use, compact, light in weight, and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a top plan view of a portion of a semi-automatic rifle embodying the present invention.

Figure 2 is a view in vertical longitudinal section, taken substantially on the line 2-2 of Figure 1.

Figure 3 is a fragmentary view in cross section through the upper portion of the rifle, taken substantially on the line 3-3 of Figure 2.

Figure 4 is a fragmentary view in cross section, taken substantially on the line 4-4 of Figure 2.

Figure 5 is a view in side elevation, showing the bolt retaining member.

Figure 6 is a view in front elevation of the bolt.

Figure 7 is a detail view in top plan of the sear-actuating link.

Referring now to the drawings in detail, it will be seen that the embodiment of the invention which has been illustrated comprises a frame 1. The frame 1 has formed longitudinally therein a bore 2 in which a bolt 3 is slidable. The usual recoil spring 4 is operatively connected at 5 to the rear end portion of the bolt 3.

A firing pin 6 is slidably mounted in the lower portion of the bolt 3 for engagement and actuation by a spring loaded hammer 7. A coil spring 8 is provided in the forward portion of the bolt 3 for retracting or resetting the firing pin 6.

A sear 9 releasably secures the hammer 7 in cocked position. A link or bar 10 is mounted for longitudinal sliding movement and slight vertical movement in the lower portion of the frame 1. A trigger 11 is connected to the rear end portion of the bar 10. An upstanding abutment 12 is provided on the forward end portion of the bar

10 for engagement with the sear 9 for releasing the hammer 7.

The abutment 12 is a portion of an arm 13 which projects upwardly and forwardly from the forward end portion of the bar 10. The arm 13 is engaged in an opening 15 in a pin 14 which is slidably mounted in the frame 1. A coil spring 16 yieldingly engages the pin 14 beneath the bolt 3. The bolt 3 has formed in its lower portion a recess 17 for the reception of the pin 14.

The upper portion of the bolt 3 is formed to provide, at an intermediate point, an upstanding, transverse abutment or shoulder 18. Extending forwardly from the shoulder 18 to a point in spaced relation to the forward end of the bolt 3 is a longitudinal bore 19. Longitudinal slots 20 in the upper portion of the bolt 3 communicate with the bore 19 at the sides thereof. The slots 20 are in registry with longitudinal grooves or channels 21 in the opposed walls of the frame 1.

A plunger 22 is slidable in the bore 19, said plunger including a beveled rear end 23. A bar 24 is mounted transversely in the plunger 22 and is slidable in the slots 20 and the grooves 21. A coil spring 25 in the forward portion of the bore 19 yieldingly urges the plunger 22 rearwardly in the bolt 3. The firing pin 6 is formed to provide a cam surface 26 at an intermediate point. A pawl 27 is pivotally mounted in the bolt 3 above the firing pin 6. One end of the pawl 27 is engaged with the plunger 22 for releasably securing said plunger in its forward or retracted position against the tension of the spring 25 through the medium of a spring 28. The other end of the pawl 27 is engaged with the cam surface 26 for disengaging said pawl from the plunger 22 when the firing pin 6 is driven forwardly by the hammer 7.

The upper portion of the frame 1 is recessed or 40 cut out to accommodate a vertically swinging retaining latch 29 for the bolt 3. The latch 29 is substantially U-shaped in cross section and comprises a pair of rearwardly extending side legs 30 which straddle the upstanding portion 31 of the frame 1. A pin 32 pivotally secures the legs 30, at an intermediate point, to the frame portion 31. Thus, the latch 29 is mounted on the frame 1 for limited swinging movement in a vertical plane. Coil springs 33 beneath the rear end 45 portions of the legs 30 yieldingly resist upward or opening swinging movement of the latch 29. Mounted transversely in the free or forward end portion of the latch 29 is a rod or the like 34 which is engageable with the abutment 18 for releasably securing the bolt 3 in forward position.

It is thought that the operation of the invention will be readily apparent from a consideration of the foregoing. Briefly, with the elements in the positions shown in Figure 2 of the drawings, the gun is ready to be fired. The trigger 11 is pulled for actuating the sear 9 through the medium of the slidable bar 10, thus releasing the hammer 7. The hammer 7 strikes and drives the pin 6 forwardly in the bolt 3 against the tension of the spring 8 for firing the cartridge 35 in the chamber 36. When the firing pin 6 is driven forwardly by the hammer 7, the pawl 27 is caused to release the plunger 22 by the cam surface 26. Thus, while the bullet is traveling through the barrel of the gun, the plunger 22 is moving rearwardly in the bore 19 under the influence of the coil spring 25. After the bullet has left the barrel of the rifle, the cam surface 23 of the plunger 22 engages the pin 34 and swings same, with the latch 29, upwardly against the tension of the coil springs 33. When the pin or rod 34 is thus forced upwardly out of engagement with the abutment 18, the bolt 3 moves rearwardly in the frame 1 against the tension of the recoil spring 4. As the bolt 3 moves rearwardly in the bore 2, the end portions of the bar 24, traveling in the grooves 21, engage the rear ends of the grooves for arresting and resetting the plunger 22 against the tension of the coil spring 25. The plunger 22 is secured in reset position by the pawl 27 under the influence of the spring 28. Of course, when the bolt 3 reaches retracted position, the spent cartridge is ejected and a new one is caused to enter the chamber 6 in the usual manner. From here on, the action or operation of the gun is substantially similar to that of other semi-automatic weapons now on the market. It will thus be seen that a construction and arrangement has been provided whereby the opening of the bolt relative to the time that

the bullet leaves the barrel of the rifle is positively controlled. This relationship is controlled by the strength of the coil spring 25 and the position of the forwardly moving firing pin 6 at the time it causes the pawl 27 to release the plunger 22. The upper portion of the frame 1 is transversely notched at 31 to accommodate the rod or pin 34. A hand cocking bolt 38 is mounted on the forward end portion of the bolt 3. A slot 39 in one side of the frame 1 communicates with the adjacent groove 21 to facilitate insertion of the member 24 in the bolt 3. Cartridges in the magazine well 40 of the rifle are shown at 41.

It is believed that the many advantages of a semi-automatic rifle constructed in accordance with the present invention will be readily understood, and although a preferred embodiment of the gun is as illustrated and described, it is to be understood that changes in the details of construction and in the combination and arrangement of parts may be resorted to which will fall within the scope of the invention as claimed.

What is claimed is:

A semi-automatic rifle comprising a frame, a bolt slidable in said frame, a firing pin slidable in the bolt, a latch pivotally mounted on the frame and engageable with the bolt for releasably securing said bolt against rearward sliding movement in said frame, a spring actuated plunger slidable in the bolt for disengaging the latch for releasing said bolt, and means operable by the firing pin for releasably securing the plunger in retracted position, said means including a spring pressed pawl pivotally mounted on the frame and engaged with the plunger, and a cam surface on the firing pin engaged with said pawl for disengaging same from the plunger.

RAYMOND FREDERICK GERFEN.
